FREQUENCY SENSITIVE SYSTEM

Karl Rath, New York, N. Y., assignor to Radio Patents Corporation, a corporation of New York

Application April 5, 1940, Serial No. 328,006

11 Claims.

(Cl. 250—20)

The present invention relates to frequency variation response or sensitive systems of the type in which the magnitude, and possibly sign, of an output current or voltage depends on the departure of the frequency of an alternating signal or of the resonant frequency of a tuned circuit from some particular frequency.

Devices and circuits of this nature have various uses, for example for producing a tuning control potential in automatic tuning systems embodied in a radio receiving apparatus, in frequency control or stabilizing arrangements in radio transmitters, and for demodulating frequency modulated carrier signals. Other uses are for translating or converting small mechanical movements affecting the capacity and/or inductance of a resonant circuit so as to cause a detuning of the frequency of an auxiliary oscillator in electronic control apparatus and for various other applications as will become evident from the following disclosure.

The invention is more particularly concerned with frequency variation response systems of the type comprising a phase shifting circuit, preferably a tuned circuit for establishing at two points of this circuit alternating potentials differing in phase by an amount varying with the relative departure between the frequency of an alternating potential impressed upon the circuit and the tuning frequency to which the circuit is resonant, and further means for combining the said two potentials so as to obtain an electrical or mechanical output containing a component proportional to their product, that is, in turn to said frequency departure to be detected or converted.

In a commonly known arrangement for detecting or converting frequency variations, a primary and a secondary electrical circuit, at least one of which is tuned to a predetermined frequency, are coupled with each other inductively to form what is known as a band-pass filter network. If an alternating potential is impressed upon such a filter the phase difference between the potentials established at the high potential ends of the primary and secondary circuits varies proportionately to the relative frequency departure between the impressed signal and the tuning frequency to which the network is resonant. Thus, in a band-pass filter comprising two inductively coupled resonant circuits equally tuned to a predetermined frequency, the potentials at the high potential sides of the circuits will be shifted in phase by 90° relative to each other if the input frequency

equals the tuning frequency of the circuits. This frequency departure will vary in either direction with respect to the normal 90° phase difference proportionately as the input frequency 5 decreases below or increases beyond the tuning frequency of the circuits. The two potentials of varying relative phase difference are combined such as by the aid of a balanced detector capable of producing an output current or potential containing a component proportional to their product, that is, varying in amplitude proportionately to the relative phase difference between the impressed potentials and in turn to the relative frequency departure between the input signal 10 and the tuning frequency to which the circuits are resonant.

Arrangements of the above and other known type have the disadvantage that due to the mutual coupling between the circuits constituting the phase shifting network their adjustment is critical and requires frequent rebalancing as well as careful screening from other parts of the apparatus in which the circuit is incorporated if reliable and consistent results are to 15 be expected in addition to other well known defects and drawbacks.

Accordingly, it is an object of the present invention to substantially overcome the drawbacks inherent in the known arrangements for frequency detection or demodulation and to provide a novel system of the above character which is both simple in design and easy to adjust and balance and which will maintain its balance for a considerable length of time compared with the 20 circuits known in the prior art.

Another object is to provide a frequency variation response circuit of the type mentioned hereinabove comprising at least two coupled circuits to establish potentials differing in phase 25 proportionately to the relative frequency variations to be detected and wherein mutual reactance between the circuits is substantially eliminated and adjustment of either circuit enabled substantially independently of the other circuit.

Further objects and advantages of the invention will become more apparent as the following detailed description proceeds taken with reference to the accompanying drawings forming 30 part of this specification, and wherein:

Figures 1 to 4 illustrate various modifications of frequency variation response or detecting circuits designed according to and embodying the principle of the invention,

55 Figure 5 shows a diagram illustrating the em-

bodiment of the invention in a radio receiver to effect an automatic tuning control.

Figure 6 is a block diagram illustrating the embodiment of the invention as a detector or demodulator in a frequency modulation radio receiver.

Like reference numerals identify like parts in the different views of the drawings.

With the above mentioned objects in view, the present invention contemplates the use of what is known as a variable space charge or virtual cathode in an electron discharge tube serving as a coupling element or impedance between circuit elements of a variable phase shifting system to produce potentials having a relative phase relation varying proportionately to the frequency variations to be detected or converted. If, in an electron discharge tube provided with a cathode, a control grid near said cathode, a plate or further grid and a screen grid located between said control grid and said plate and being maintained at a high positive potential with respect to said cathode, said plate or further grid is operated at cathode potential or biased negatively with respect to the cathode and an oscillating input potential is impressed upon said control grid, a concentrated electron space charge or virtual cathode will be formed in the space between said screen grid and said plate or further grid, said virtual cathode having a charge density varying in accordance with said oscillating potential. Said plate or further grid, according to the present invention, is biased and operated in such a manner that it collects substantially no electrons and accordingly is purely capacitatively coupled with said variable space charge or virtual cathode in the manner described. This variable space charge which is due to a varying concentration of electrons which have passed the openings of the positive or screen grid and are retarded by the anode is equivalent to a fluctuating electron supply source and for this reason is referred to as a virtual cathode.

Such a variable space charge or virtual cathode induces a corresponding variable charge on said plate or further grid which gives rise to a displacement current in the plate circuit of the same frequency as that of the oscillations impressed upon the control grid. The induced plate potential is displaced in phase by 90° relatively to the grid alternating potential due to the capacitative coupling or generation of the plate potential by electrostatic induction and in this respect the operation of a tube used in this manner differs basically from the common electron tube circuits operated with a high positive potential on the plate as an output electrode in which case the plate potential is in anti-phase relation to the grid alternating or input potential.

In accordance with the present invention, capacitative or space charge coupling of the above type is utilized to effect a varying phase shift between a pair of potentials derived from a resonant network and combined to produce an output varying in intensity or amplitude proportionately to the frequency variations of an input potential or of the natural or resonant frequency of a tuned circuit or network.

Referring to Figure 1, there is shown a frequency sensitive circuit which may serve for converting an input signal of varying frequency impressed by way of terminals *a*—*b* into a potential varying in amplitude proportionately to the input frequency variations derived from output

terminals *c*—*d*. It is to be understood, however, that the invention is not limited to the conversion of frequency variations of a potential or current but applies equally to converting variations of the natural or tuning frequency of a resonant circuit as will be explained in greater detail hereafter.

In Figure 1, the input alternating voltage which may be a high frequency signal of varying frequency is impressed by way of coupling coil 12 upon a resonant circuit comprised of an inductance 10 shunted by a condenser 11 and coupled to the grid 16 and cathode 15 of an electron tube 14 which comprises further a screen grid 17 maintained at a high positive potential with respect to the cathode in a manner well known and a plate 18. A further tuned circuit comprising an inductance 20 shunted by a condenser 21 is connected between the plate 18 and cathode 15 in series with a source of potential 22, to provide a suitable negative steady bias for the plate 18 with respect to the cathode. The source 21 may be omitted and the negative plate bias produced solely by a resistance and condenser shunting network 15' in the cathode-to-ground lead. If desirable, the plate 18 may be at cathode potential to suit any existing requirement. As pointed out hereinabove, if the circuit 20, 21 is tuned to a frequency equal to that of the impressed alternating voltage a concentrated space charge or virtual cathode is formed adjacent to the plate 18 causing a potential to be induced on the plate of the frequency of and having a phase displaced by 90° with respect to the input potential applied to the grid 16. Thus, if the circuits 10—11 and 20—21 are equally tuned to a predetermined frequency and assuming that the input potential impressed by way of terminal *a*—*b* is of the same frequency, the potentials at the high potential points A, B of the tuned circuits 10—11 and 20—21 will be exactly 90° out of phase and this phase difference will be increased or decreased, respectively, in proportion to the departure of the input signal frequency from the tuning frequency to which the circuits 10—11 and 20—21 is resonant.

The potentials at the points A, B of varying relative phase are combined in a suitable manner to produce a common output including a component proportional to their product, that is, in turn to the frequency variations of the input potentials impressed by way of terminals *a*—*b*. In the example shown, the combining device takes the form of an electronic modulator or mixer tube 25 comprising a cathode 26, followed in the order named by a first control grid 27, a positive or screen grid 28 being maintained at a suitable positive potential with respect to the cathode, a second control grid 29 and an anode or plate 30. The potential established at the high potential side of the circuit 10—11 (point A) is impressed in the example shown directly upon the first control grid 27 of tube 25, while the potential established at the plate 18 or high potential side of the resonant circuit 20—21 (point B) is impressed upon the second control grid 29 of the tube 25 by way of an adjustable potentiometer resistance 23 and coupling condenser 24, the former serving to establish proper amplitude relation between the potentials impressed upon the grids 27 and 29 of the modulating or mixer tube 25. Item 24' is a leak resistance for the grid 29 and item 26' is a grid biasing network comprising a resistance-condenser shunt

combination inserted in the cathode-to-ground lead of the tube.

There is thus produced in the output circuit of the tube 25 by reason of the inter-modulation of the potentials on the grids 27 and 29 a component proportionate to the product of the control potentials; that is, in turn to the relative phase difference between the potentials established at points A and B. This component varies therefore in amplitude proportionately to the frequency variations of the input potential impressed by way of terminals a—b. This output component is segregated by the aid of a selective coupling device comprising a load impedance such as ohmic resistance 32 by-passed to ground by condenser 33 in the output circuit of the tube 25. The output potential may be derived from a portion of the load resistance 32 which is further by-passed by a condenser 34 applied to the output terminal c—d by way of a coupling condenser 35. The circuits 10—11 and 20—21 are advantageously carefully shielded from each other and from the rest of the apparatus by means of grounded screen indicated at 10' and 20', respectively.

It will be understood that a system shown in Figure 1 has the advantage over arrangements known in the prior art that the resonant circuits 10—11 and 20—21 may be adjusted and balanced individually without mutual reaction, and that the balance will be maintained for a considerable length of time as a result of the uni-lateral coupling between the circuits in a direction from the input to the output of the tube 14. The output coupling network 32—33—34—35 shown in Figure 1 is designed for translating periodic variations such as sound or video currents in the case of a frequency modulated input radio signal comprising a carrier frequency varying in either direction according to the magnitudes of the periodic modulating signals. If the frequency variations to be detected are of an aperiodic, i. e. a slow or progressive nature as in the case of automatic tuning control arrangements, the output coupling network is suitably modified to be responsive to variations of this character as shown more specifically in Figure 5 to be described later.

As pointed out the circuit described is well suited for demodulating signals of varying frequency impressed by way of input terminals a—b. According to a further embodiment of the invention the circuit may also serve for converting variations of the resonant frequency of a tuned circuit, preferably the circuit 20—21 into corresponding amplitude variations of an output current or potential supplied at terminals c—d. In this case an alternating potential of fixed frequency is impressed upon input terminals a—b whereby the tuning variations caused by changes of the inductance 20 or of the capacity 21 will result in a corresponding variation of the relative phase difference between the potentials established at points A, B and a conversion or translation of the natural tuning variations in substantially the same manner as described hereinbefore. Thus, for instance, the capacity change effected by a slight mechanical movement affecting the tuning frequency of the resonant circuit may be translated into corresponding amplitude variations of electrical energy for indicating or controlling purposes for use in various scientific or industrial electronic control devices known in the art.

Referring to Figure 2, there is shown an alter-

native method of combining the potentials established at points A, B to produce output energy having a frequency responsive amplitude in accordance with the invention. In the example illustrated an aperiodic input circuit is provided by the omission of the condenser 11, the remaining elements associated with the tube 14 being substantially similar to those of Figure 1. In order to combine the potentials established at points A and B having a varying relative phase relation there is provided a ring modulator or rectifier bridge circuit adapted to produce output energy having an amplitude proportional to the product of a pair of input potentials and comprising four rectifying elements of any suitable type such as dry rectifiers 36, 37, 38, 39. The rectifiers are connected to form a closed circuit and arranged in like sense as regards their current passing directions. One of the voltages to be compared and established between point A and ground is impressed upon one pair of diagonal points or apices of the bridge circuit by way of a coupling coil 40 arranged in inductive relation with the input coupling inductance 10, while the other voltage established between point B and ground is impressed upon the remaining apices of the bridge circuit by way of coupling coil 41 arranged in inductive relation with the inductance 20 of the resonant circuit. The output is derived from suitable points preferably the mid points of the induction coils 40, 41 and applied to output terminals c—d by way of a transformer 42. A pair of choke coils 43 and 44 are advantageously inserted in the output leads 35 to prevent high frequency input currents from directly passing to the output circuit.

A further modification of an inventive system is shown in Figure 3 which embodies a further vacuum tube as a phase inverter to produce an additional potential (at point C) having a phase opposite to the phase of the input potential (at point A). By combining the quadrature potential established at point B with either of the potentials at points A and C sum and difference potentials are obtained which latter are rectified and combined differentially to produce an output varying in accordance with the product of the potentials at points A and B and including a frequency responsive component in a manner similar to that described hereinbefore. In the example shown a composite vacuum tube is provided comprising a pentode section associated with the variable phase shift circuit and a triode section to serve as a phase inverter. The tube 50 provided for this purpose includes a common cathode 51, a pentode section comprising an input grid 52, a positive or screen grid 53 maintained at a high positive potential with respect to the cathode, and a suppressor grid 54 directly tied to the plate 55, and a triode section comprising the cathode 51, a control grid 56 and an anode 57. Both sections are suitably shielded from each other such as by means of a grounded screen in a manner well understood. Item 58 is a biasing network comprising a resistance bypassed by a condenser and inserted in the cathode-to-ground lead of the tube. The plate 55 of the pentode section is connected to ground through a tuned circuit comprising an inductance 60 shunted by a condenser 61 and suitably shielded from the remaining parts of the system by means of a grounded screen 60'. In this manner the pentode section of the tube provides a space charge coupling between the input circuit and the circuit 60—61 thereby establishing a po-

tential on the plate 55 (point B) having a phase varying relative to the phase of the input potential (point A) in proportion to the relative frequency departure of the impressed potential from the tuning frequency to which the circuit 60-64 is resonant in the manner described in detail hereinabove.

The grid 56 of the triode section is coupled, in the example shown, directly to the high potential side of the input circuit (point A) and the plate 57 of the triode section is connected to the plus pole of a space current source through a coupling impedance preferably an ohmic resistance 68'. There is established in this manner on the plate 57 (point C) a potential having a phase opposite to the phase of the input potential applied to grid 52. There are further shown in Figure 3 a pair of double triode tubes 62 and 63 serving for combining the potential at point B with either of the potentials at point A and point C or in other words, to produce sum and difference potentials from the potentials at points A and B and to rectify and to differentially combine the thus obtained sum and difference potentials to produce a frequency responsive output. For this purpose points A, B and C are connected with the double triode tubes 62 and 63 having control grids 64, 65 and 66, 67, respectively, as follows: Point B is connected to grids 64 and 67 of one of the triode sections of each tube, point A is connected to the grid 66 of the remaining triode section of tube 63, while point C is coupled to the grid 65 of the remaining triode section of tube 62 by way of coupling condenser 67' and grid leak resistance 68. The plates of the tubes are tied together and connected each to one of the output terminals c-d shunted by a load impedance 69 having its mid point connected to the plus pole of a source of space current. There is produced in this manner across the terminal c-d the differential of the rectified sum and difference of the potentials established at points A and B. This differential potential will include a component varying proportionately to the relative phase between the potentials at points A and B; that is, in turn to the relative departure of the frequency of the input potential from the tuning frequency to which the circuits 60-64 is resonant.

Referring to Figure 4, there is shown still another modification of a frequency sensitive system according to the invention. According to this exemplification the input signals of varying or fixed frequency are impressed upon the grids 52 and 56 of the pentode and triode sections of a composite tube 50 in substantially the same manner as shown in Figure 3, whereby potentials will be established at points B and C whose relative phase varies proportionately to the variations of the input frequency or the variations of the resonant frequency of the circuits 60-64 as the case may be. In the present example the potentials established at points B and C are impressed upon the control grids 72 and 74 of a composite pentode diode tube 70 by way of coupling condensers 82 and 80 and grid leak resistances 83 and 81, respectively. The tube 70 further comprises a common cathode 71, a main anode or plate 75, a diode plate 76 arranged to cooperate with the cathode 71, and a positive or screen grid 73 arranged between the control grids 72 and 74 and maintained at a suitable positive potential relative to the cathode. Item 77 is a grid biasing network comprising a resistance shunted by a condenser and inserted in the cathode-to-ground lead. The plate 75 is 75

connected to the plus pole of a space current source through a tuned resonant circuit comprising an inductance coil 84 shunted by a condenser 85 and a resistance 86. This resonant circuit is in turn coupled to a secondary resonant circuit comprising an inductance 87 shunted by a condenser 88, whereby both circuits form a band-pass coupling network suitably shielded from the remaining parts of the system by means of a screen 84'. The purpose of the resistance 86 shunting the resonant circuit 84-85 is to sufficiently broaden the frequency response to encompass the whole range of frequency variations impressed upon the input a-b in case of receiving a wide band frequency modulated signal.

In an arrangement of this type the frequency modulated signals are converted into corresponding amplitude modulated signals in the circuit 84-88 by the combined action of the grids 74 and 72. The thus obtained amplitude modulated signal is impressed from the circuit 87-88 upon the diode plate 76 whereby a frequency responsive or demodulated potential is produced across the diode load resistance 88' shunted by a smoothing condenser 89 and connected across output terminals c-d, in a manner described in detail in my co-pending patent application, Ser. No. 318-972, filed February 14, 1940 entitled "Frequency variation response circuit" which matured into Patent 2,248,197 issued July 8, 1941.

Referring to Figure 5, there is shown a radio receiving system in block diagram form embodying a frequency responsive system according to the invention serving as a discriminator for an automatic tuning arrangement incorporated in the receiver. Radio signals received by an antenna 90 are impressed upon a radio frequency amplifier 94 by way of a coupling transformer 93. The amplified radio frequency signals are combined in a first detector or mixed with signals of different frequency generated by a local oscillator 96 to produce intermediate frequency signals which are effectively and selectively amplified in an intermediate frequency amplifier 97. The amplified intermediate frequency signals are applied to a second detector and audio amplifier 98 supplying an output energizing a suitable translating device such as a loud speaker 99. Fractional intermediate frequency energy is derived by way of terminals a-b and impressed upon the frequency responsive system which in the example shown is of substantially the same type as illustrated in Figure 1 with the exception of the output coupling network for the tube 25. The latter in the example shown comprises a coupling resistance 32 in series with the space current source 32' and a condenser shunted between ground and the plate of tube 25. Such a coupling will be responsive to aperiodic and slow variations proportional to the departure between the frequency of the intermediate signals and the tuning frequency of the resonant circuit 20-21 which latter in this case is tuned to the intermediate frequency of the amplifier 97 for which the system is designed. The tune detecting potential thus obtained across terminals c-d is impressed upon a suitable tuning control element of the local oscillator 96 such as upon the grid of an electronic reactance tube controlling the frequency of the local oscillating tank circuit in such a manner as to maintain the departure between the signal frequency and the intermediate frequency of the receiver within a desired minimum range.

Referring to Figure 6 there is shown in block

diagram form a receiver for frequency modulated signals comprising an antenna 90 connected by way of coupling coil 100 to a tuned input circuit comprising an inductance 101 shunted by a condenser 102 and a band spread resistance 103. After amplification in a radio frequency amplifier 104, the radio frequency signals are converted into signals of intermediate frequency in a first detector-mixer stage 106 having associated therewith a local oscillator 105. The intermediate frequency signals are amplified in an intermediate frequency amplifier 107 and thereafter freed from any spurious amplitude modulation in a limiter 108 of known construction. The pure frequency modulated signals obtained from the output of the limiter 108 are impressed upon input terminals *a*—*b* of a frequency modulation detector which may consist of any one of the systems described hereinabove and serves to demodulate the frequency modulation representing the intelligence being transmitted into a corresponding output signal to be further amplified in an audio amplifier 109 and applied to a suitable translating device such as a loud speaker 110.

It will be evident from the foregoing that the invention is not limited to the specific circuits and arrangement of parts disclosed and described herein for illustration but that numerous variations and modifications may be resorted to as will suggest themselves to those skilled in the art, all coming within the broad scope and spirit of the invention as defined in the appended claims. Thus, for instance, the combination of the phase shifted potentials established at points A and B may be effected purely mechanically by applying potentials or currents derived from points A and B to different coils of an electrodynamometer. The force of attraction between these coils is then proportional to the product of the potentials and accordingly will vary in the required manner with the relative departure of the input frequency from the tuning frequency of the resonant circuit and may be adapted for any suitable purpose such as for moving a pointer or operating a relay or the like. The specification and drawings are accordingly to be regarded in an illustrative rather than a limiting sense.

I claim:

1. A frequency variation response circuit comprising a source of alternating current, resonant impedance means, the relative frequency of said alternating current with respect to the resonant frequency of said impedance means being variable, an electron discharge tube comprising at least a cathode, a control grid, a screen grid and a further electrode, all arranged substantially in the order named, means for impressing potential from said source upon said control grid, means for maintaining said screen grid at a positive steady potential with respect to said cathode, further means for maintaining said electrode at a relatively low steady potential with respect to said screen grid to substantially prevent a steady electron current to and to bring about a variable electron space charge in the vicinity of said further electrode, means for coupling said impedance means to said electrode and cathode, separate means exterior of said tube for combining the alternating potentials at said control grid and said electrode to produce output energy proportional to their product, and further means for segregating from said output energy a component varying proportionately to

the relative frequency departure of said impressed potential from the resonant frequency of said impedance means.

2. A frequency variation response circuit comprising a source of high frequency current, resonant impedance means, the relative frequency of said current with respect to the resonant frequency of said impedance means being variable, an electron discharge tube comprising at least a cathode, a control grid, a screen grid and further electrode, all arranged substantially in the order named, means for impressing potential from said source upon said control grid, means for maintaining said screen grid at a positive steady potential with respect to said cathode, further means for maintaining said electrode at a negative steady potential with respect to said cathode to substantially prevent a steady electron current to and to bring about a variable space charge in the vicinity of said electrode, means for coupling said impedance means to said electrode and cathode, separate means exterior of said tube for combining the high frequency potentials at said control grid and said electrode to produce output energy proportional to their product, and further means for segregating from said output energy a component varying proportionately to the relative frequency departure of said impressed potential from the resonant frequency of said impedance means.

3. A frequency variation response circuit comprising a source of high frequency current, resonant impedance means, the relative frequency of said source with respect to the tuning frequency of said resonant impedance means being varied, a first electron discharge tube comprising at least a cathode, a control grid, a screen grid and a further electrode, means for impressing potential from said source upon said control grid, means for maintaining said screen grid at a steady high positive potential with respect to said cathode, further means whereby said electrode is maintained at a relatively low steady potential with respect to said screen grid to substantially prevent electrons from being conveyed to said electrode and to bring about a variable space charge adjacent to said electrode, means for coupling said resonant impedance means to said electrode and cathode, a second electron tube comprising at least a cathode, a pair of control grids, a screen grid arranged between said control grids and an anode, means for maintaining the screen grid and anode of said second electron tube at positive steady potentials with respect to the cathode, means for impressing each of the high frequency potentials at said control grid and electrode, respectively, of said first electron tube upon one of the control grids of said second electron tube, and coupling impedance means in the anode circuit of said second electron tube effective in developing output energy having an amplitude varying proportionately to the relative phase variations between said control potentials.

4. A frequency variation response circuit comprising a source of high frequency current, resonant impedance means, the relative frequency of said source with respect to the tuning frequency of said resonant impedance means being varied, an electron discharge tube comprising at least a cathode, a control grid, a screen grid and a further electrode, means for impressing potential from said source upon said control grid, means for maintaining said screen grid at a relatively high steady positive potential with

respect to said cathode, means for maintaining said electrode at a relatively low steady potential with respect to said screen grid to substantially prevent electrons from being conveyed to said electrode and to bring about a variable space charge adjacent to said electrode, means for coupling said resonant impedance means to said electrode and cathode, a modulator comprising four rectifying elements arranged in like sense to form a bridge circuit, first circuit means for impressing a first high frequency voltage established between said grid and cathode upon one pair of apices of said bridge circuit, second circuit means for impressing a second high frequency voltage established between said electrode and cathode upon the remaining pair of apices of said bridge circuit, an output circuit connected between tapping points of said first and second circuit means, and coupling impedance means in said output circuit effective in developing output energy having an amplitude varying proportionately to the relative phase variations between said first and second high frequency voltage.

5. A frequency variation response circuit comprising a source of high frequency current, resonant impedance means, the relative frequency of said source with respect to the tuning frequency of said resonant impedance means being varied, an electron discharge tube comprising at least a cathode, a control grid, a screen grid and a further electrode, means for coupling said source to said control grid and cathode, means for maintaining said screen grid at a relatively steady high positive potential with respect to said cathode, further means for maintaining said electrode at a relatively low steady potential with respect to said screen grid to substantially prevent electrons from being conveyed to said electrode and to bring about a variable space charge adjacent to said electrode, means for coupling said resonant impedance means to said electrode and cathode, circuit means for producing sum and difference potentials from the potentials established at said control grid and said electrode, respectively, means for rectifying said sum and difference potentials, and further means for differentially combining the rectified potentials.

6. A frequency variation response circuit comprising a source of high frequency current, resonant impedance means, the relative frequency of said source with respect to the tuning frequency of said resonant impedance means being varied, a first electron discharge tube comprising at least a cathode, a control grid, a screen grid and a further electrode, means for coupling said source to said control grid and cathode, means for maintaining said screen grid at a relatively high steady positive potential with respect to said cathode, further means for maintaining said electrode at a relatively low steady potential with respect to said screen grid to substantially prevent electrons from being conveyed to said electrode and to bring about a variable space charge adjacent to said electrode, means for coupling said resonant impedance means to said electrode and cathode, a second electron tube having at least a cathode, a control grid and an anode, means for impressing potential from said source upon the control grid of said second electron tube, circuit means for combining the potential established at said electrode of said first electron tube with either of the potentials established at the grid of said first electron tube and at the anode of said second electron tube, means

10 for rectifying the combined potentials, and further means for differentially combining the rectified potentials.

7. A frequency variation response circuit comprising a source of high frequency current having a varying frequency, a tuned circuit resonant to a predetermined fixed frequency, an electron discharge tube comprising at least a cathode, a control grid, a screen grid and a further electrode, all arranged substantially in the order named, means for impressing potential from said source upon said control grid, means for maintaining said screen grid at a steady positive potential with respect to said cathode, further means for maintaining said electrode at a relatively low steady potential with respect to said screen grid to substantially prevent a steady electron current to and to bring about a variable space charge in the vicinity of said electrode, means for coupling said tuned circuit to said electrode and cathode, separate means exterior of said tube for combining the high frequency potentials upon said control grid and said electrode to produce output energy proportional to their product, and further means for segregating from said output energy a component having an amplitude varying proportionately to the relative frequency departure of said impressed potential from the resonant frequency of said tuned circuit.

8. A frequency variation response circuit comprising a source of frequency modulated signals, a fixedly tuned circuit resonant to the center frequency of said signals, an electron discharge tube comprising at least a cathode, a control grid, a screen grid and further electrode, all substantially in the order named, means for impressing signal potential from said source upon said control grid, means for maintaining said screen grid at a steady positive potential with respect to said cathode, further means for maintaining said electrode at a relatively low steady potential with respect to said screen grid to substantially prevent a steady electron current to and to bring about a variable space charge in the vicinity of said electrode, said tuned circuit being connected to said electrode and cathode, separate means exterior of said tube for combining the high frequency potentials at said control grid and said electrode to produce output energy proportional to their product, and impedance means to segregate from said output energy a component having an amplitude varying proportionately to the frequency variations of said signals.

9. A frequency variation response circuit comprising a source of alternating current having a substantially fixed frequency, a tuned circuit, the resonant frequency of said tuned circuit being variable, an electron discharge tube comprising at least a cathode, a control grid, a screen grid and a further electrode, all arranged substantially in the order named, means for impressing potential from said source upon said control grid, means for maintaining said screen grid at a steady positive potential with respect to said cathode, further means for maintaining said electrode at a relatively low steady potential with respect to said screen grid to substantially prevent a steady electron current to and to bring about a variable space charge in the vicinity of said electrode, said tuned circuit being connected to said electrode and cathode, separate means exterior of said tube for combining the alternating potentials at said control grid and said electrode to produce output energy proportional

to their product, and further means for segregating from said output energy a component having an amplitude varying proportionately to the variations of the resonant frequency of said circuit.

10. A frequency variation response circuit comprising an input circuit carrying high frequency currents, an electron discharge tube having means for producing an electron space current, means including circuit connections from said input circuit to said tube for varying said space current in accordance with said high frequency currents, an electrode in said tube with means for applying thereto a steady bias potential whereby substantially no electrons are conveyed to said electrode from said space current and a concentrated electron space charge is set up adjacent to said electrode, resonant impedance means, the relative frequency of said high frequency currents with respect to the tuning frequency of said resonant impedance means being varied, means for connecting said resonant impedance means to said electrode to produce a displacement current therethrough by coupling with said space charge, further means for deriving a pair of control potentials from said input circuit and said resonant impedance means having a relative phase varying according to the relative frequency departure of said high frequency currents from the tuning frequency of said resonant impedance means, and means for producing output energy having an amplitude varying in proportion to the product of said control potentials.

11. A frequency variation response circuit comprising an input circuit carrying high frequency currents, an electron discharge tube having means for producing an electron space current, means including circuit connections from said input circuit to said tube for varying said space current in accordance with said high frequency currents, an electrode in said tube with means for applying thereto a steady negative bias potential whereby substantially no electrons are conveyed to said electrode from said space current and a concentrated electron space charge is set up adjacent to said electrode, a resonant circuit, the relative frequency of said high frequency currents with respect to the tuning frequency of said resonant circuit being varied, means for connecting said resonant circuit to said electrode to produce a displacement current therethrough by coupling with said space charge, means for deriving a pair of control potentials from said input circuit and said resonant circuit having a relative phase varying according to the relative frequency departure of said high frequency currents from the tuning frequency of said resonant circuit, further means for producing output energy having an amplitude proportional to the product of said control potentials, and means for deriving a component from said output energy varying in amplitude proportionately to said frequency departure.
